The ornamental design for a backpack for laptop and tablet computers, as shown and described.

DESCRIPTION

FIG. 1 is a perspective view of a backpack for laptop and tablet computers showing my new design; FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of a second embodiment of my design of FIG. 1;

FIG. 9 is a front elevational view of FIG. 8; and,

FIG. 10 is a right side elevational view of FIG. 8.

The structural features depicted by broken lines have been provided to illustrate portions of the backpack for laptop and tablet computers that form no part of the claimed design.

The second embodiment discloses an exposed zipper in place of the covered zipper disclosed in the first embodiment.

Views of the second embodiment that are not shown are identical to FIGS. 3, 4, 6, and 7.
